UNITED STATES PATENT OFFICE.

JOSEPH C. GILARDONE, OF READING, PENNSYLVANIA, ASSIGNOR OF ONE-THIRD TO SOLOMON S. MILLER AND ONE-THIRD TO GEHRKE KNITTING MILLS, A COPARTNERSHIP, BOTH OF READING, PENNSYLVANIA.

EMBROIDERING MACHINE.

Application filed February 2, 1923. Serial No. 616,455.

To all whom it may concern:

Be it known that I, JOSEPH C. GILARDONE, a citizen of the Republic of Switzerland, residing at Reading, in the county of Berks 5 and State of Pennsylvania, have invented certain new and useful Improvements in Embroidering Machines, of which the following is a specification.

This invention relates to improvements in 10 embroidery machines, and it pertains more particularly to machines for embroidering stockings.

Heretofore, it has been the practice, when 15 embroidering seamless stockings, to cut the stocking for a great part of its length, to permit it to be stretched on a frame, so that both sides of the stocking could be embroidered, after which the "cut" was sewed up again.

20 This method is costly, and in addition, forms a seam up the back of the stocking.

In my present invention I have devised a means of embroidering the seamless stocking without cutting it.

25 The invention contemplates a stocking holding frame over which the stocking is slipped, means for holding the stocking securely in position on the frame while one side is being embroidered, after which the 30 frame is reversed, to bring the opposite side of the stocking in line with the embroidery needle. When the embroidery is completed, the stocking is slipped from the frame, completed.

35 The invention is more fully described in the following specification and clearly illustrated in the accompanying drawings, in which:—

Figure 1 is a front elevational view of a 40 portion of the machine, showing several of the embroidery units.

Figure 2 is an enlarged view of one of the embroidery units, in position in the frame of the machine.

45 Figure 3 is a central vertical sectional view of the unit taken through Figure 2.

Figure 4 is a cross-sectional view through 4—4 of Figure 2.

Familiarity with the general construction 50 of embroidery machines employing the pantograph mechanism is assumed, and the details of such mechanism are not disclosed, having no bearing on the invention here involved.

I have shown only sufficient of the structure to clearly show how my present invention may be applied to machines of this character, in which a large number of articles, such as stockings, may be embroidered simultaneously.

The numeral 1 designates the stationary frame of the machine, and the numeral 2 designates the shuttle frame bar, which is also stationary and which carries the shuttle frame 3. The numeral 4 designates the shuttle bar which carries a series of shuttle control posts 5. These posts are each formed with an enlarged head 6, provided with an angularly arranged slot 7, and each slot is adapted to ride on a pin 8, thus giving to 70 each shuttle post an angular movement with relation to the vertical frame when the bar 4 is actuated through any well known shuttle bar actuating mechanism, not shown. The numeral 10 designates the shuttle slides, 75 in which the shuttles 11 are located, and in which the upper ends of the control posts 5 are arranged to move at an angle corresponding with the angle of the slots in the posts 5. The shuttle bar 4, when the machine is in operation, is given a reciprocating movement in the direction indicated by the arrows A in Figure 2, so that this movement of the shuttle, in the direction indicated, will be easy and free from strain of any 85 kind.

The numeral 15 designates the stocking holding frame, any number being employed, depending on the length of the machine and the number of stockings to be embroidered 90 at one time. These frames are box-like bodies, with open panels at front and rear, at which points the embroidery is to be done. The stockings are slipped over these frames, from above and a cap 18 is placed 95 over the top of the frame, engaging and holding that portion of the stocking which remains there while the body of the leg portion is drawn down over the open front and rear portions.

To this cap I secure, at two opposite ends, pivotally mounted clamping arms 20, the lower extremities of which are engaged by hooks 21 on the lower portion of the frames, and these arms bear against the stocking 105 and hold it securely in position, as against turning, on the frame.

These stocking holding frames are pro-

vided with seating pins 22 at their lower extremities, adapted to position the frames on the supports 24, which supports are carried by the machine frame uprights 25, and 5 26 designates a head clamp by means of which each stocking frame is held in position from vertical movement with relation to the supports 24.

In operation, the shuttle bar is moved, in 10 the direction indicated by the arrow, with the usual actuating mechanism for devices of this character, and this movement will determine the movement of the shuttle 11 in the slides 10, which latter is located within 15 each of the box like stocking frames 15, while the embroidering needles, indicated by the numeral 28, will be presented from the outside of the stocking, as indicated in Figure 3, and these needles will, as is usual 20 in such cases, be carried and actuated by the pantograph device, not shown, but under the guidance of the operator.

It is evident that the details of construction may be modified in many details, without departing from the spirit of my invention, which consists of a device in the form 25 of a stocking frame for holding a seamless stocking in position to be embroidered at two opposite points, and without first cutting the stocking.

Having thus described a simple device for carrying out this invention, and its purposes, I do not desire to limit myself to the exact construction so described, but,

35 What I claim and desire to secure by Letters Patent is:—

1. In a stocking embroidering machine, the combination of an embroidering mechanism including a shuttle, a shuttle carrier, a

series of shuttle control posts, each post having an enlarged head provided with an angularly arranged slot and a pin on which each post may ride, with a stocking holding frame comprising a hollow box-like body adapted to receive and accommodate the shuttle within its walls and means for actuating the embroidering mechanism and shuttle to embroider two opposite points of the stocking without removing it from the frame.

2. In an embroidering machine, the combination of a series of shuttles, carried by a shuttle bar and supported on shuttle posts carried by said bar, said posts having enlarged heads provided with angularly arranged slots, pins on which the slotted posts ride, means for conveying an angular reciprocating movement to the shuttle, a casing or frame over which a stocking may be placed without cutting, means for securely holding the stocking in position on the frame, and means for embroidering the stocking on both sides without removing the stocking from the frame.

3. The combination in a stocking embroidering machine, of a series of stocking holding frames each adapted to receive a stocking, means for holding the stocking on the frame and means for embroidering said stocking, comprising a shuttle adapted to move inside the stocking holding frame and to co-act with the needle working from the outside of the frame, a shuttle bar, a series of angularly slotted shuttle control posts carried by said bar and pins on which the slotted posts ride.

In testimony whereof I affix my signature.

JOSEPH C. GILARDONE.
